UNITED STATES PATENT OFFICE.

FRED PATEE, OF DENVER, COLORADO.

REFRIGERATOR-CAR.

1,256,162.

Specification of Letters Patent. Patented Feb. 12, 1918.

Application filed February 23, 1912. Serial No. 679,460.

To all whom it may concern:

Be it known that I, FRED PATEE, a citizen of the United States, residing at Denver, in the county of Denver and State of Colorado, 5 have invented certain new and useful Improvements in Refrigerator-Cars, of which the following is a specification.

This invention relates to improvements in refrigerator cars. The object of this invention is to provide an economical construction for cars, more especially for those cars designed for use as refrigerator cars. Another object of this invention is to provide a car with a thermally insulated chamber in 15 which perishable freight, or particularly food stuffs may be carried and maintained at a uniform temperature without the danger of rotting by being exposed to a circulation of moist air. Other objects will be apparent from the specification and appended claims, and from the drawings, in which—

Figure 1 is a transverse section of a car embodying my improved construction.

Fig. 2 is a fragmentary, vertical longitudinal section, the car being broken in two places to indicate the arrangement of the exhaust ventilators.

Fig. 3 is a transverse detail section showing the corner arrangement of the car.

Fig. 4 is a detail section along the line 4, 30 4 of Fig. 1.

Like numerals refer to like elements throughout the drawings.

10 designates the siding forming the foundation of the ends and walls. This siding 10 is secured to the framework which is composed of the horizontal frame members or beams 11 and the vertical frame members or beams 11' running between the 35 members 11.

Secured to the outside of the siding is the metal lathing 12, preferably of the sort formed with the ribs 12'. When this lathing is secured to the siding 10, as will be apparent, dead air spaces 13 are formed between the rib portions 12' and the outer surface of the siding 10. Furthermore, this use of the ribbed lathing is advantageous in securing the outside coating 14, preferably of 45 asbestos, as shown in the drawing.

The roof, as shown in Figs. 1 and 2, of the drawings, is similarly constructed to the walls, with the exception that an outer protecting sheet 15 of corrugated metal may be 50 laid on and secured to the coating of asbestos.

Interiorly of the siding 10 in the spaces between the side beams 11 and 11' is placed a filler of thermally insulating material 16. For this filler I preferably use a composition of asbestos, ground cork and plaster of Paris, although plain asbestos may be used. 60

Upright metal I-beams 17 are arranged at spaced intervals in the sides and ends of the car. Located at the bottom of the car and 65 having their ends adjacent the lower extremities of the uprights 17 are the cross beams 18. The uprights 17 have one flange secured by screw bolts or other means to the inner surfaces of the frame members 11 and 70 11'. The cross beams 18 may be secured at their extremities to the side beams 17 by rivets or other means, as indicated in the drawings.

Carried by the side beams 17 interiorly 75 thereof are the inner walls 19 comprising on the outside a layer of asbestos 20 and on the inside a corrugated sheet of metal 21 by which is carried the coating of asbestos 20. An inner bottom 22 runs between the side 80 walls 19 and is of the same construction.

Some distance below the inside of the car is arranged a floor 23 forming the roof of the packing chamber A which is inclosed by the side and end walls 19, top 23 and bottom 22. The top 23 is composed of a sheet of corrugated metal 24 sloping slightly downward on each side to the central portion 24'. The corrugations of the sloping portions 24 run toward the central portion 90 24' which is formed with corrugations running longitudinally of the car, as shown in Fig. 1 of the drawings. Supported upon the corrugations of the corrugated members 24 are the longitudinal strips 25 of wood or 95 other material. Below this member 24 and carried thereby is an insulating layer of asbestos 26 forming the top surface of the packing chamber A. The top of the car and the floor 23 and the side and end walls 19 100 together form an ice chamber B. Hatchways 26^a communicate therewith through which ice may be supplied.

In one side of the ice chamber B I provide an opening 27 at the upper portion 105 thereof, while at the other side of the ice chamber I provide an opening 28 adjacent the floor of said chamber, for a purpose to be hereinafter described. It will be noticed that air spaces between the adjacent uprights 17 and cross beams 18 extend clear around the packing chamber. Through 110

these air passages or circuits a current of cold air from the ice chamber is intended to travel. The inner surface of the filler 16 and the cross beams 11, 11' are coated 5 with a coating of water-proofed asbestos 30, as shown in Fig. 4 of the drawings. This will prevent absorption of the moisture by the said coating and frame members. Ice supplied to the ice chamber 10 B will rest on the longitudinal strips 25 and against the longitudinal strips 26' secured to the sides and ends of said chamber to protect the same. Water caused by the melting 15 of the ice will be carried by the sloping portions of the corrugated sheet 24 to the central portion 24' thereof and may be conveyed along the longitudinal depressions therein to a convenient drain opening. The location of the openings 27 and 28 in the 20 ice chamber will cause a circulation of cold air to pass out through the opening 28 since the same is lower than the opening 27, around the air spaces between the side and cross beams, the upper portion of the other 25 side of the car, whence as it becomes warmer it may either circulate around the ice through the opening 27 and be recooled or it may be drawn out of the car entirely by use of the exhaust ventilators 31 having 30 vanes 32 adapted to keep them in an exhaust position, as shown in Fig. 2 of the drawings. These ventilators are of conventional type and are not claimed as new by me.

Ventilating pipes 33 depend from and 35 carry the ventilators 31. These pipes depend into the spaces between adjacent side beams 17 at the left hand side of the car in the construction shown in Fig. 1, and are provided with plug dampers 34 at their 40 lower ends pivoted at 35. An operating rod 36 is pivotally secured to these dampers 34 and terminates in an operating handle 37 located without the car. By operation of this handle 37 the dampers 34 may be operated to close or open the pipes 33 when it 45 is desired to dispense with the forced ventilation. It will be noted that in my improved construction the packing chamber A is altogether shut off from the ice chamber 50 B. By this means any entrance of cold moist air to the load is prevented. The circulation of the cold air around the packing chamber A will prevent the same from being affected by the outside temperature of 55 the car and the contents of the packing chamber A will be thermally insulated from any heat changes, not only by the circulation of the cold air, but also by the protecting outer wall construction. The asbestos 60 coatings 20 and 26 not only assist in the thermal insulation of the packing chamber A, but also prevent sweating on the outside of the corrugated metal sides and ends 65 and bottom 22, any such sweating being absorbed by the said asbestos. By the use of

an outer layer of asbestos 14, painting of the car is dispensed with if so desired and protection against fire is much enhanced. The use of the ribbed metal lathing 12 not only aids in securing the outside coating 70 of asbestos in place, but also provides dead air spaces 13 which greatly assist in the thermal insulation of the interior of the car. I do not desire to be restricted to the form of construction shown in the drawings and described in the specification beyond the scope of the appended claims. 75

I claim:

1. A refrigerator car comprising top, bottom, end and side walls, a partition running substantially the entire length of said car located between the top and bottom thereof and forming an ice chamber and a packing chamber at the top and bottom respectively of said car, said chambers being thermally insulated from each other and from the exterior of said car, means to circulate air from adjacent one side of said ice chamber around the walls of said packing chamber to adjacent the other side of said ice chamber, and means to extract the air from adjacent said last named side of said ice chamber after circulation. 90

2. A refrigerator car, comprising top, bottom, end and side walls, said side walls and bottom being provided with communicating air spaces therein, said car being provided with a transverse partition dividing the same into an upper ice chamber and a lower packing chamber, the walls of said packing chamber being constructed to prevent the circulation of air therethrough, heat-insulating coatings for the walls of said communicating air spaces, and means to permit air to pass from the lower part of said ice chamber 100 at one side of said car into said air spaces and thence from said air spaces at the other side of said car into the upper part of said ice chamber. 105

3. A refrigerator car comprising top, bottom, end and side walls, said sides and bottom being provided with communicating air spaces therein, said car being provided with an ice chamber adjacent the top thereof and a packing chamber below said ice chamber, 110 said packing chamber being insulated from said ice chamber, means to circulate air from said ice chamber through the air spaces in said walls and bottom, the latter forming continuous passages for such circulation, 115 said ice chamber being in communication adjacent the bottom thereof with the air passages in one of said walls and in communication adjacent the top thereof with the other of said walls, whereby a thermo-siphon circulation may be set up from said ice chamber through the passages in said walls and bottom of said car back to said ice chamber, and means to positively extract said air at or 120 near the completion of its circulation. 125

4. A refrigerator car comprising top, bottom, end and side walls, said side walls and bottom being provided with communicating air passages, an ice chamber adjacent the top thereof, and a packing chamber below said ice chamber, the latter being insulated from the former, said ice chamber being in communication with said air passages in said walls, whereby circulation of air may be established around said packing chamber, the surfaces of said air passages being coated with moisture-proof material.

5. A refrigerator car having inner and outer side walls and upper and lower floors spaced apart to provide communicating air spaces, the outer surfaces of said inner walls and the lower surface of said upper floor being provided with heat-insulating coverings, other heat-insulating coverings for the upper 20 surface of the lower floor and the inner surfaces of said outer walls, said last-named heat-insulating coverings being provided on their upper and inner surfaces with moisture-proof coatings, a transverse partition 25 extending between said inner side walls and dividing the space in said car into an ice chamber and a packing chamber, and means to permit air to circulate from said ice chamber through said air spaces around said 30 packing chamber, and thence back to said ice chamber at the other side of said car.

6. A refrigerator car comprising top, bottom, end and side walls, a partition running

substantially the entire length of said car between the top and bottom thereof to form 35 an ice chamber and a packing chamber at the top and bottom, respectively, of said car, said partition being formed of sheet metal inclined downwardly from each side of the car with corrugations formed therein extending transversely of the car, and other corrugations formed in the center portion thereof extending longitudinally of the car.

7. A refrigerator car comprising top, bottom, end and side walls, a partition running 40 substantially the entire length of said car between the top and bottom thereof to form an ice chamber, a packing chamber at the top and bottom, respectively, of said car, said partition being formed of sheet metal 45 inclined downwardly from each side of the car with corrugations formed therein extending transversely of the car, other corrugations formed in the center portion thereof extending longitudinally of the car, said 50 sheet metal partition being provided on its underside with a layer of heat insulating material, and means for circulating air from said ice chamber around said packing chamber.

In testimony whereof I have subscribed my name.
